(57) **CLAIM**

I claim the ornamental design for lottery sign for segmented indicators, as shown and described.

DESCRIPTION

FIG. 1 is a front perspective view of a lottery sign with segmented indicators according to my design; the broken lines in FIG. 1 are for illustrating environmental features that forms no part of the claimed design; it is to be understood that the lottery sign with segmented indicators may be contained within any housing and that the exact shape, size or geometry of the housing forms no part of the claimed design;

FIG. 2 is a front view of the lottery sign with segmented indicators;

FIG. 3 is a top view of the lottery sign with segmented indicators;

FIG. 4 is a bottom view of the lottery sign with segmented indicators;

FIG. 5 is a rear view of the lottery sign with segmented indicators; and,

FIG. 6 is a left side view of the lottery sign with segmented indicators, the right side view being a mirror image thereof. The lottery sign with segmented indicators is shown with a symbolic break in its length and width. The appearance of any portion of the article between the break lines forms no part of the claimed design.
